PROCESS FOR REFINING HYDROCARBON OILS BY MEANS OF HALOGEN COMPOUNDS

Ernst Terres, Berlin, Germany, and Josef Moos, New York, and Erich Saegebarth, Jackson Heights, N. Y., assignors to Edelcanu Gesellschaft, m. b. H., a corporation of Germany

No Drawing. Original application March 22, 1935, Serial No. 12,528. Divided and this application October 25, 1937, Serial No. 170,965

11 Claims. (Cl. 196—13)

This invention relates to the refining of hydrocarbon mineral oils, such as petroleum oils, and oils made from coal tar and bituminous coal tar, to improve their qualities for lubrication, motor fuel, solvents and other uses, and is a division of our application Ser. No. 12,528, filed March 22, 1935, for Processes for refining hydrocarbon oils by means of halogen compounds.

For the refining of mineral oils, selective solvents, mixtures of selective solvents or mixtures of a selective solvent with a non-selective solvent are already known. These solvents separate the main group of hydrocarbons by dissolving for example the aromatic and unsaturated components and leaving undissolved the saturated or paraffine-like groups. Some selective solvents remove also the naphthenes together with the aromatics and unsaturates.

The hydrocarbon compounds belonging to the groups of aromatics and unsaturates and—to a certain degree also those of the naphthalene groups—are well known as non-resistant against oxidation. They are further characterized by a low A. P. I. gravity, low flash and fire point, by high carbon residue and by an unfavorable viscosity-temperature relationship. The removal of the mentioned classes of hydrocarbons results therefore in a greatly improved refined oil which is equal to or in some instances even better, than the best mineral oils known, such as fractions from Pennsylvania crude. Whereas fractions made from Pennsylvania crudes have a satisfactory viscosity-temperature characteristic, they show nevertheless high Conradson carbon figures and require consequently expensive refining to yield a finished oil which satisfies modern demand for use in internal combustion engines.

Our invention teaches the use of selective solvents which produce finished oils of a quality superior to Pennsylvania oils insofar as the viscosity temperature relationship of stocks of any origin is improved to that or above that of Pennsylvania oils and also insofar as the carbon residues are much lower. The extraction by means of our solvents further greatly facilitates the finishing procedure inasmuch as the solvent extraction removes all or most of the color bearing compounds with the extracted fraction.

For reasons of simplicity we will refer in the following to the refined oil as "raffinate" and to the undesirable or extracted fraction as "extract."

An object of this invention is to refine hydrocarbon oils by means of selective solvents in order to produce stable raffinates which, when properly

finished, will fulfill the most severe specifications adopted by science for the specific products in question.

Our selective solvents are adaptable to the refining of naphthas in which case a saturated fraction or raffinate is produced such as is frequently used as special solvent, for example Stoddard's Solvent; the dissolved fraction or extract contains the aromatic and unsaturated components which have great value on account of their high octane number. These extracts may either be used as motor fuel directly or as a blending material for upgrading other gasolines of less satisfactory specifications.

Likewise our solvents are suitable for refining kerosenes, gasoils, transformer oils, turbine oils, the various grades of lubricating oil distillates and of residual stocks.

Depending upon the stocks to be refined and depending upon the raffinate quality desired, the solvents may be used either alone or in combination with auxiliary solvents. These auxiliary solvents have to fulfill three different objects, namely that of (1) increasing or (2) decreasing solvent power or that of (3) improving the selectivity of our selective solvents.

The representatives of class 1 of auxiliary solvents which increase the solvent power are characterized by dissolving hydrocarbon oils entirely and at the same time by being miscible with the selective solvent in each proportion. Examples of this class of auxiliary solvents are the aromatics (such as benzol, toluol, xylol, etc.), hydroaromatics, such as cyclohexane, the non-selective aliphatic and aromatic halogen derivatives, the non-selective ketones, esters, ethers and others.

Representatives of class 2 of auxiliary solvents, which decrease the solvent power of our selective solvents, are identified by being miscible with our selective solvents to a certain degree or in any proportion and by not dissolving hydrocarbon oils at all or only to a certain extent. For example, water and alcohols belong to this class of auxiliary solvents.

The members of class 3 of auxiliary solvents which improve the selectivity, are characterized by dissolving the hydrocarbon oils entirely but they are not miscible in each proportion with selective solvents. This third class of auxiliary solvents will dissolve the hydrocarbon oils to be treated and, upon adding one or more of our selective solvents, will remain mostly in the raffinate phase, whereas the first and second group of auxiliary solvents (namely those which are

miscible with our selective solvents) will go mainly into the extract phase. Representatives of the third class of auxiliary solvents are, for example, low boiling paraffine hydrocarbons such as propane, butane, etc., or mixtures thereof.

We have found that solvents of the class of symmetric polybromohydrines, such as 1,3 dibromohydrine ($\text{CH}_2\text{Br}-\text{CHOH}-\text{CH}_2\text{Br}$) and 1,2,3, tribromohydrine ($\text{CH}_2\text{Br}-\text{CHBr}-\text{CH}_2\text{Br}$), possess an especially good selectivity and at the same time excellent solvent power, and these solvents are therefore especially adapted for refining of hydrocarbon oils. A further advantage of these solvents, as compared with other known selective solvents, is given by their unusually high specific gravity, which results in a much larger difference of gravity between the two layers and consequently the separation of raffinate and extract layer is greatly facilitated. The use of centrifuges for this purpose, as necessary for many other known solvents, is therefore eliminated and moreover the settling time is much less than with the other known solvents.

For carrying out our invention we charge the stock to be treated to a counter current refining system, (comprising three or more mixing and settling stages) and introduce dibromohydrine or tribromohydrine, or mixtures thereof, at the opposite end of the unit. In this operation the undesirable fractions of the stock are dissolved by the counter current washing action and the raffinate is left in undissolved form containing a certain percentage of the solvent. The solvent quantities which we use and the treating temperatures depend upon the nature of the stock and upon the quality of the raffinate desired. Normally we employ from 100 to 150% of the solvent. The raffinate and extract layers are separately charged to the respective solvent recovery systems.

Instead of using one of our mentioned selective solvents for the extraction alone, they may be employed simultaneously. If deemed advantageous, we use one or more of our selective solvents in combination with an auxiliary solvent either to increase or to decrease the solvent power or to improve the selectivity as described above.

Instead of recovering the solvents from the hydrocarbon groups by distillation we sometimes effect this separation by washing with a different solvent in which our selective solvents are soluble but not the hydrocarbons.

As specific examples for further demonstration of our invention, we cite the following:

Example 1

A mixed base lubricating oil distillate of 17.3° A. P. I. gravity was extracted with 100% by volume 1, 3 dibromohydrine

at 68° F.; the raffinate and extract phases were separated from each other and the solvent was recovered by distillation. The specifications of the raffinate are shown in the table below.

Example 2

A sample of the same mixed base lubricating oil distillate of 17.3° A. P. I. as used in Example 1 was extracted with 100% by volume 1, 2, 3 tribromohydrine ($\text{CH}_2\text{Br}-\text{CHBr}-\text{CH}_2\text{Br}$) at +14° F. The solvent was recovered from the raffinate and extract solutions by distillation. The results of the extraction and the improvements

obtained thereby will be seen from the following table.

	Untreated oil	Raffinate obtained with dibromohydrine	Raffinate obtained with tribromohydrine	5
Yield volume per cent.....	100	99	71	
*A. P. I.....	17.3	20.6	22.3	
Saybolt vis. at 210° F.....	108.6	101	92.4	
Viscosity index.....	45	64	75	10

The examples describe treatments made by multiple batch extraction and they serve mainly for demonstrating the refining effect of our solvents. In commercial operation the counter current method of extraction will be used employing either a mixing and settling tank equipment or a so-called tower mixer.

We claim the following as our invention:

1. A process for refining hydrocarbon oils by extracting the latter in batch or counter current with symmetric dibromohydrine at suitable temperatures, effecting separation of the layers, separating the layers from each other and recovering the solvent from the layers.

2. A process for refining hydrocarbon oils by extracting the latter in batch or counter current with tribromohydrine at suitable temperatures, effecting separation of the layers, separating the layers from each other and recovering the solvent from the layers.

3. A method of refining a mineral oil comprising extracting the oil with a solvent of the class consisting of symmetric polybromohydrines to produce a separation into two phases containing respectively paraffinic and non-paraffinic constituents, separating the phases from each other and recovering the solvent therefrom.

4. A method of refining a mineral oil comprising mixing the oil with a solvent of the class consisting of symmetric polybromohydrines and adjusting the temperature to produce a separation into two oil containing phases, separating the phases from each other and recovering the solvent therefrom.

5. A method of refining a mineral oil comprising extracting the oil with a solvent of the class consisting of symmetric polybromohydrines, in admixture with an auxiliary solvent to produce a separation into two phases containing relatively paraffinic and non-paraffinic constituents, separating the phases from each other and recovering the solvents therefrom.

6. A method of refining a mineral oil comprising extracting the oil with 1, 3 dibromohydrin to produce a separation into two phases containing respectively paraffinic and non-paraffinic constituents, separating the phases from each other and recovering the solvent therefrom.

7. A method of refining a mineral oil comprising mixing the oil with 1, 3 dibromohydrin and adjusting the temperature to produce a separation into two oil containing phases, separating the phases from each other and recovering the solvent therefrom.

8. A method of refining a mineral oil comprising extracting the oil with 1, 3 dibromohydrin, in admixture with an auxiliary solvent to produce a separation into two phases containing relatively paraffinic and non-paraffinic constituents, separating the phases from each other and recovering the solvents therefrom.

9. A method of refining a mineral oil comprising extracting the oil with 1, 2, 3 tribromohydrin to produce a separation into two phases contain-

- ing respectively paraffinic and non-paraffinic constituents, separating the phases from each other and recovering the solvent therefrom.
10. A method of refining a mineral oil comprising mixing the oil with 1,2,3 tribromohydrin and adjusting the temperature to produce a separation into two oil containing phases, separating the phases from each other and recovering the solvent therefrom.
11. A method of refining a mineral oil com-
- prising extracting the oil with 1,2,3 tribromohydrin, in admixture with an auxiliary solvent to produce a separation into two phases containing relatively paraffinic and non-paraffinic constituents, separating the phases from each other and recovering the solvents therefrom. 5
